HINGE DOWEL FOR TRANSVERSE JOINTS OF
CONCRETE ROADWAYS AND THE LIKE

Alan E. Brickman, Rostravor Township, Westmoreland County, Pa., assignor to The American Steel and Wire Company of New Jersey, a corporation of New Jersey

Application November 23, 1938, Serial No. 242,119

6 Claims. (Cl. 94—18)

The present invention relates to doweling devices for transverse joints of concrete highways.

An object of the present invention is the provision of a hinged dowel member which will permit free movement of the pavement slabs in expansion, contraction or curling.

A further object of the present invention is the provision of a dowel device formed from castings and assembled so as to provide a hinged action at the transverse joint.

Other objects and advantages will become apparent as the description proceeds and reference is had to the accompanying drawings, in which:

Figure 1 is a sectional plan through a transverse joint, showing the dowel device of the present invention in elevation with a portion thereof in section to show the hinged connection between the members forming the doweling device;

Figure 2 is a sectional side elevation of the dowel in position at a transverse expansion joint of a concrete highway;

Figure 3 is a view similar to Figure 2, only showing the position of the doweling device under contraction due to the expansion of the concrete slabs;

Figure 4 is a view similar to Figure 3, showing the relationship between the elements forming the hinge dowel device where expansion takes place at the top surface of the concrete slabs in advance of the bottom surface; and,

Figure 5 is a detailed elevation showing the method of assembling the hinge dowel device.

In the drawings, the dowel device of the present invention comprises generally three malleable iron castings designated generally at A, B, and C. These castings, when assembled to produce the hinged doweling action, are positioned through a conventional joint filler E and embedded within the concrete slab sections.

The member A forming one part of the dowel assembly may, for the sake of convenience, be designated as a "hinge housing" comprising a body portion 2 from which extends, at right angles to the main plane of said body portion, spaced horizontally positioned arms 3, which are provided with nubs 4 in order to secure better distribution of stresses and provide means for holding this hinge housing A in the concrete bond. This main body portion 2 is provided with a beveled portion 5 favorable to the flow of wet concrete and eliminates the danger of forming voids. Extending laterally from the main body portion 2 are ears 6.

The member B may, for the purpose of convenience, be designated the "dowel member," and

comprises a diametral portion 7 having outwardly extending bosses 8 with bearing edges 9 extending rearwardly from said diametral portion 7 and adapted to be slidably positioned within the member C which, for convenience, has been designated as the "dowel socket."

The dowel socket comprises a body portion 10 having rearwardly extending ribs 11, which ribs diverge inwardly toward each other and terminate in nubs 12 in order to hold said dowel socket in the concrete bond. Upon the top surface of said dowel socket, at a point rearward of said main body portion 10, there is provided an upwardly extending nub 13 to assist in maintaining said dowel socket bonded within the concrete. This dowel socket is so constructed and arranged as to provide a central opening within which is slidably positioned the dowel member B so that the bearing edges 9 of said dowel member B slidably engage the inward projections 14 formed upon the inner surface of said dowel socket. A tap-hole is provided upon the upper surface of said dowel socket to receive a set-screw 15 for holding the doweling device in initial assembly prior to the pouring of the concrete.

A filler member 16, of cork or other compressible material, forms a closure for the open end of the dowel socket C.

A filler block 17 of conventional design is provided with the necessary cut out portions to permit extension of the dowel therethrough.

In assembling the present doweling device, the dowel B is inserted through the main body portion 2 of the hinge housing a sufficient distance to permit the diametral portion 7 to extend on the other side of the main body portion 2 of the hinge housing. A coating of paint or the like material is applied to the surface of said diametral member 7 prior to insertion of said member into the main body portion 2 of said hinge housing in order to form a cleavage action for the assembly and assure free working hinge action after bonding in the concrete. The diametral portion 7 having been positioned in the hinge housing, the ears 6 are bent down from their dotted line position, as shown in Figure 5, to the full line position so as to securely retain the diametral head portion 7 within the hinge housing. The dowel B is then passed through the aperture formed in the compressible joint filler 17 and into the dowel socket C so that the bearing edges 9 slidably engage the inward projections 14 formed on said dowel socket. The set-screw is then tightened to bear upon the bearing edge 9 of said dowel so as to initially maintain the as-

sembly with sufficient rigidity to withstand han-
dling and pouring of the concrete. The set-
screw, however, will yield to the high expansion
and contraction forces of the concrete after set-
ting and thereby permit the hinge action of the
doweling device to function upon expansion and
contraction of the concrete slabs.

Under the present day practice of concrete
highway construction, observation tests and
physics have disclosed that temperature changes
on the exposed surface of the roadway cause ex-
pansion and contraction of the top surface of
the roadway which may differ greatly from the
expansion and contraction of the bottom or un-
der surface of the roadway.

Due to this variation in the degree of expansion
and contraction between the top and bottom
surfaces of the roadway, action is set up be-
tween the slabs which results in slab curling.
While the weight of the concrete pavement gen-
erally overcomes this curling action, it does so
with the detrimental result of setting up high
stresses which are relieved only by objectionable
cracks. At transverse joints in concrete road-
ways where the slabs and reenforcement end,
curling will take place if the doweling means
does not have sufficient rigidity to restrain the
same. Under the present construction, these de-
fects are overcome due to the hinged doweling
means at the transverse joints which permit end
curling and relieve these objectional stresses.

While I have shown and described a specific
embodiment of the present invention, it will be
seen that I do not wish to be limited exactly
thereto, since various modifications may be made
without departing from the scope of the inven-
tion, as defined by the following claims.

I claim:

1. In a transverse joint for concrete highways,
means permitting free movement of the pave-
ment slabs during expansion and contraction of
the pavement slabs at the joint, said means com-
prising a housing embedded in a concrete slab,
a dowel receiving socket embedded in an adjoin-
ing concrete slab and a dowel hingedly connected
to said housing and slidale within said dowel
receiving socket.

2. A doweling device for transverse joints of
concrete roadways comprising a housing, a dowel
member and a dowel socket, said dowel member
hingedly connected to said housing and slidale
within said dowel socket.

3. A doweling device for transverse joints of
concrete roadways comprising a housing, a dowel
member and a dowel socket, said dowel member
hingedly connected to said housing and slidale
within said dowel socket, said dowel socket pro-
vided with means for holding the doweling de-
vice in initial assembly prior to the pouring of
the concrete.

4. A doweling device for transverse joints of
concrete roadways comprising a housing, a dowel 15
member, a dowel socket, said dowel member
hingedly connected to said housing and slidale
within said dowel socket, said dowel socket pro-
vided with means for holding the doweling de-
vice in initial assembly prior to the pouring of 20
the concrete and means on said housing and
dowel socket for anchoring said doweling device
in the concrete.

5. A transload device for expansion and con-
traction joints comprising, in combination with a 25
joint filler, a housing embedded in a concrete
slab, a dowel hingedly supported by said housing
and extending through said joint filler and a
dowel receiving socket member embedded in the
adjoining concrete slab for slidably receiving the 30
dowel member.

6. A transload device for expansion and con-
traction joints comprising, in combination with
the joint filler, a housing embedded in a con-
crete slab of the roadway, a dowel member hing- 35
edly supported in said housing and a dowel socket
member embedded in the adjacent concrete slab
of the roadway, said dowel extending through
the joint filler and into slidale contact with the
dowel receiving socket to provide a hinge and 40
slidale movement between said transload ele-
ments to simultaneously compensate for slab end
curling and expansion and contraction of the
adjoining concrete slabs.

ALAN E. BRICKMAN.
